UNITED STATES PATENT OFFICE

VALENTINE C. LUPPERT, OF WILLIAMSPORT, PENNSYLVANIA

PENCIL SHARPENER

Application filed December 14, 1929. Serial No. 414,077.

This invention relates to improvements in pencil sharpeners, and more especially to a novel pencil sharpener either of the hand operated rotatable type or stationary type.

5 The primary object of the invention is to furnish a pencil sharpener of this character which is especially designed to permit ordinary safety razor blades to be used as the cutters thereof, so that dull safety razor 10 blades which are ordinarily discarded, may be utilized for a considerable period of time for pencil sharpening purposes.

Another object of the invention is to provide a pencil sharpener adapted to use as 15 cutters, the conventional double edged flexible razor blades.

A still further object is to furnish such a pencil sharpener in which novel means are employed for clamping and holding the 20 razor blades in proper position to function as cutters in the device.

Another object is to provide a pencil sharpener of this type, including a novel knock-down casing, made up of a number of 25 sections, which may be readily attached to the supporting frame; one of these sections being readily removable at all times to permit quick access to the blades for adjusting or replacing the latter, and another section being quickly 30 detachable to allow for the discarding of pencil shavings.

With the foregoing objects outlined and with other objects in view which will appear as the description proceeds, the invention 35 consists in the novel features hereinafter described in detail, illustrated in the accompanying drawings, and more particularly pointed out in the appended claims.

40 Referring to the drawings, Fig. 1 is a side elevation of a rotatable embodiment of my improved sharpener.

Fig. 2 is an end elevation of the same.

Fig. 3 is a longitudinal vertical sectional view taken on the line 3—3 of Fig. 2.

45 Fig. 4 is a transverse vertical sectional view on the line 4—4 of Fig. 3.

Fig. 5 is a horizontal sectional view on the line 5—5 of Fig. 3.

50 Fig. 6 is a developed perspective view of the parts forming the casing of this device.

Fig. 7 is a vertical sectional view of a stationary type pencil sharpener in which my improved cutting head is incorporated and vertically arranged.

Fig. 8 is a similar view of a modified form 55 of the stationary type with the cutting head positioned horizontally instead of vertical.

In the embodiment of the invention shown in Figs. 1 to 6 inclusive, 7 designates a supporting standard having a base 8 which may 60 be secured to any suitable supporting surface by means of screws or the like.

A bearing 9 is mounted at the top of the standard, and its inner end enlarges into a flared portion 10, which carries a ring 11 65 having an annular groove 12 in its periphery, which is arranged between a small annular flange 13, and a larger annular flange 14. If the parts 10 and 11 are made integral, of course the groove will be in the flared portion 70 10.

The operating shaft of the machine is horizontally disposed, and is designated 15, and it is journaled in the bearing 9. An inner portion of this shaft is enlarged as shown at 75 16, so as to bear against the flared portion 10 of the support, and the outer end of the shaft is fixedly connected to a crank handle 17, which may be secured to the shaft by any suitable means such as a screw 18.

The pencil receiving tube or cutting head 19 is rigidly united with, and projects from the part 16 of the shaft, and this tube or head has lateral wings 20, arranged on opposite sides of the axis of the shaft, and each provided with a curved or plane bearing surface 21 which merges into the tapered bore 22 of the tube or cylinder, owing to the fact that slots 23 are provided in opposite sides of the tube.

It may be seen from Fig. 3 that these slots, as well as the bearing surfaces 21 converge inwardly toward the intermediate portion 16 of the shaft, so that the blades 24 of the machinery are inclined or properly positioned 95 to shape a pencil end into conical form, when a pencil is inserted through the open end of the tube, and the shaft is rotated, while the pencil is held from rotation.

Each blade 24 may be of the flexible dou-

ble-edged safety razor type, and as before stated, I intend to use for this purpose, ordinary safety razor blades which are too dull for use in shaving the face. Each of these 5 blades bears upon the curved or flat surface 21 of one of the wings, and is held in curved or flat shape by means of a detachable curved or flat rigid metal plate 25, that may be secured to the corresponding wing by any suitable means, such as a thumb screw 26, which passes through the plate and blade, and screws into the wing 20. To prevent any rotation of either blade about its clamping screw as an axis, each wing has a pair of 10 projecting studs or pins 27 that are rigidly mounted on the wing, and pass through the usual end holes in such blades, and through suitable apertures 28 in the clamping plate 25.

This novel form of cutting mechanism is 20 combined with a specially designed casing which includes an intermediate section 29, a top section 30, and a bottom section 31. The section 29 is in the form of a yoke, and comprises a transversely extending bar 32 having an aperture 33 through which a pencil may be inserted into the mouth of the cylinder 19. Arms 34 extend inwardly from the cross bar 32, and terminate at their inner ends in opposite flanges 35 having curved 25 inner edges 36 which conform to the curvature of the groove 12 of the support. As the casing sections are made of sheet metal, which has some resiliency, it will be understood that the flanges 35 may be made to 30 grip the ring 11 by simply pulling the inner ends of the arms 34 apart so as to clear the flange 13, and then permit the flanges 35 to snap into the groove 12 and assume the position shown in Fig. 5. During such operation, the outer end of the cylinder 19 is projected through the hole 32 of the intermediate 35 section of the casing.

In order that the cutting mechanism may be readily reached for the purpose of adjusting or changing the blades, the top section 30 of the casing is detachably mounted on the intermediate section, and for guiding the lower edges of the top section are bent inwardly to provide parallel grooves 37 which 40 slidably engage tracks or flanges 38 which project outwardly from the upper edges of the intermediate section. It will be noted that the top is of parti-cylindrical shape, and one of its ends is sector-shaped, as shown at 45 39. This end, when the casing is assembled, is in substantially the same plane as the cross bar 32 of the intermediate section. The opposite end of the top is provided with an inwardly extending flange 40 that is adapted 50 to clear the flange 13 when the top is pushed inwardly, but which comes to rest against the flange 14 for limiting the inward movement of the top.

The casing section 31 which forms the shavings receiving tray, is of trough-shape, and

its side edges terminate in grooved portions 41 which slidably engage outwardly extending parallel flanges 42 at the lower edges of the intermediate portion of the casing. The outer end 43 of the shavings receptacle, when 55 the parts are assembled, is in the same plane as the end 39 of the top, so that the entire outer end of the casing is closed, but of course, the inner end of the shavings receptacle is cut away, as shown at 44, so as to clear the flange 13, but to abut against the flange 14 of the frame.

As a further improvement, I may state that the tube 19 of the sharpener is to be made sufficiently large to accommodate pencils of varying thicknesses, and for the purpose of supporting pencils of various sizes, while they are inserted in the tube, I provide the outer end of the intermediate section of the casing with a slide 45 having a plurality of different sized apertures 46, any one of which may be brought into register with the tube, by shifting the slide laterally on the casing. To allow for this sliding movement, the edges of the cross bar of the intermediate section are bent outwardly and toward each other, to provide grooves 47 to slidably receive upwardly and downwardly projecting flanges 48 of the slide.

From the foregoing description, it is believed that the operation will be clear to those familiar with devices of this character, but by way of further explanation, it may be stated that when the end of a pencil is inserted into the tube 19, the cutting edges of the blades will not only converge toward the axis of the tube, but they will be so arranged as to shape the end of the pencil into cone form, when the handle 17 is operated, and the pencil is held from rotation. I have found in actual practice, that a pair of discarded razor blades, when used for this purpose, will be efficient for considerable time, and that they will sharpen the pencils without breaking the points of the latter. Furthermore, it is a simple and easy matter to change or adjust the blades, for when the top 30 of the casing is removed, the internal mechanism is in plain view, and the thumb screws 26 can be easily reached.

It is also quite simple with the present device to discard the shavings, for after the receptacle 31 has been filled, such receptacle may be removed by simply sliding the same off the guide flanges 42.

There is another feature in this device, to which reference should be made. As the groove 12 is circular in form, the casing will occupy a vertical position, regardless of the position of the supporting frame. In other words, the supporting frame can be mounted in an upright position on a table or the like; it may be secured to a vertical wall, or it may be suspended from a shelf or the like, and in

any of those positions, the casing may be arranged vertically.

As heretofore stated, my improved cutting head may also be incorporated in a stationary pencil sharpener, that is, one in which the cutter head will be fixed in position and the pencil will be sharpened by turning the same relatively to the head. For example, a cutter head 100 (Fig. 7), similar in construction to that described in connection with the rotary cutting head, and using razor blades as cutters, may be placed in a casing 101, which may form part of a desk pad or paper weight. In such embodiment, a fixed screw 102 may project upwardly from the bottom of the casing and engage internal threads at the lower end of the cutting head, for the purpose of detachably fixing the latter within the casing. The casing may be embellished 20 on its exterior for ornamental purposes, and be provided with a removable cap 103, having a centrally disposed aperture to permit a pencil to be inserted into the tubular portion 104 of the cutting head.

25 In this form of the invention, the shavings may be removed after the cap 103 is taken off, and when it is necessary to change or adjust the blades, the cutter head can be unscrewed from the screw 102, and lifted upwardly through the open end of the casing.

Instead of arranging the cutter head vertically, the latter may be arranged horizontally in a casing 200, as shown in Fig. 8, and in this embodiment, one end 201 of the casing may 35 be detachable to allow for the discharge of chips, and for the removal of the cutter head to facilitate adjustment or changing of the blades.

The forms of the invention shown in Figs. 40 7 and 8 are intended to be part of any desk equipment, and they need not be secured to the desk, but either may be held stationary by one hand, while the other hand is used to turn the pencil relatively to the cutting head, 45 for sharpening purposes.

While I have disclosed herein what I now consider to be a preferred embodiment of the invention in such manner that the construction, operation and advantages thereof may 50 be readily understood, by those skilled in the art, I am aware that various changes may be made in the details disclosed, without departing from the spirit of the invention, as expressed in the claims.

55 Having fully described my invention what I claim as new and desire to secure by Letters Patent, is:—

1. A pencil sharpener including a stationary casing, a stationary cutting head in the 60 casing provided with a tubular portion having oppositely projecting wings and slots leading from the wings to the interior of the tubular portion, razor blades mounted on said wings and having cutting edges extending 65 through said slots and converging toward the

axis of the head, clamping plates bearing on said blades, and thumb screws securing the blades and plates to the wings, said wings being provided with means to prevent the blades from turning on the thumb screws. 70

2. A combination sharpener comprising a casing, a stationary cutting head detachably arranged in the casing and provided with a tubular portion, a wing projecting laterally from said tubular portion and having a bearing surface arranged at an angle to the axis of the tubular portion, and a blade detachably mounted on said wing, engaging said bearing surface, and having a cutting edge converging relatively to the axis of said head. 75

3. A pencil sharpener comprising a casing, a stationary cutting head, threaded means fixedly securing the cutting head to the casing, said head being provided with a tubular portion, said casing including a removable cap having an aperture through which a pencil may be inserted into said tubular portion, a wing projecting laterally from said tubular portion and having a bearing surface arranged at an angle to the axis of the tubular portion, and a blade detachably mounted on said wing, engaging said bearing surface, and having a cutting edge converging relatively to the axis of said tubular portion. 80

In testimony whereof, I have signed this specification.
